TRASH CAN CART

Ernest F. Steinhoff, Freeport, Ill., and Neal K. Steinhoff,
Verona, Wis. (both % The Steinhoff Company, Rte. 1,
Verona, Wis. 53593)

Filed July 28, 1971, Ser. No. 167,072

Term of patent 14 years

Int. Cl. D12—02

U.S. Cl. D14—3 M

Fig. 1

Fig. 2

Fig. 3

Fig. 4

FIG. 1 is an isometric view of the trash can cart embodying our new design.

FIG. 2 is an isometric view of our trash can cart with a pair of typical cans shown in dashed lines.

FIG. 3 is a side elevational view of our trash can cart.

FIG. 4 is a rear end view of our trash can cart.

The portion shown in dashed lines in FIG. 2 represents typical cans carried by our cart and is not part of our claimed design.

We claim:

The ornamental design for a trash can cart, as shown and described.
